TAPE CARTRIDGE

Kenneth A. Catto, Portland, and Harold R. Burt, Beaverton, Oreg., assignors to Data Time, Inc., Beaverton, Oreg.

Filed Mar. 31, 1972, Ser. No. 240,332

Term of patent 14 years

Int. Cl. D14—01; D16—99
U.S. Cl. D26—14 B

Fig. 1.

Fig. 2.

Fig. 3.

Fig. 4.

Fig. 5.

FIG. 1 is a top perspective view of a tape cartridge showing our new design;

FIG. 2 is a bottom perspective view of the cartridge;

FIG. 3 is a bottom plan view thereof;

FIG. 4 is an elevation of the near right side of the cartridge in FIG. 1; and

FIG. 5 is an elevation of the near left side of the cartridge in FIG. 1—the other two sides of the cartridge having substantially the same appearance.

We claim:

The ornamental design for a tape cartridge, as shown and described.
